(57) **CLAIM**

The ornamental design for a play yard, as shown and described.

DESCRIPTION

FIG. 1 is a top perspective view of a play yard showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of detail 9 shown in FIG. 1;

FIG. 10 is an enlarged view of detail 10 shown in FIG. 1;

FIG. 11 is an enlarged view of detail 11 shown in FIG. 1;

FIG. 12 is an enlarged view of detail 12 shown in FIG. 1;

FIG. 13 is an enlarged view of detail 13 shown in FIG. 1;

FIG. 14 is an enlarged view of detail 14 shown in FIG. 1;

FIG. 15 is an enlarged view of detail 15 shown in FIG. 1;

FIG. 16 is an enlarged view of detail 16 shown in FIG. 1;

FIG. 17 is an enlarged view of detail 17 shown in FIG. 1;

FIG. 18 is an enlarged view of detail 18 shown in FIG. 1;

FIG. 19 is an enlarged view of detail 19 shown in FIG. 1;

FIG. 20 is an enlarged view of detail 20 shown in FIG. 1;

FIG. 21 is an enlarged view of detail 21 shown in FIG. 1;

FIG. 22 is an enlarged view of detail 22 shown in FIG. 1;

FIG. 23 is an enlarged view of detail 23 shown in FIG. 1;

and,

FIG. 24 is an enlarged view of detail 24 shown in FIG. 2.

The dash-dash broken lines in the drawings depict portions of the play yard that form no part of the claimed design. The dot-dash broken lines represent boundaries of the enlarged portions and form no part of the claimed design.

1 Claim, 24 Drawing Sheets
